CLAIM

The ornamental design for versatile bedding article, as shown and described.

DESCRIPTION

FIG. 1 is a perspective rear view of versatile bedding article in accordance with the new design;
 FIG. 2 is a front view thereof;
 FIG. 3 is a side view thereof;
 FIG. 4 is a bottom view thereof;
 FIG. 5 is a top view thereof;
 FIG. 6 is a rear view thereof;
 FIG. 7 is a front view of the versatile bedding article shown on a person; and,
 FIG. 8 is a rear view of the versatile bedding article shown on a person.

The small broken lines illustrate stitching and form part of the claimed design. The large broken lines illustrating the human form in FIGS. 7 and 8 show environment that forms no part of the claimed design.
